UNITED STATES PATENT OFFICE

WILLIAM B. CHAPMAN, OF COLORADO SPRINGS, COLORADO

GRATE STRUCTURE

Application filed March 28, 1927. Serial No. 179,015.

My invention relates to furnaces of heating plants, power plants and other furnaces in which subbituminous coal is burned. My object is to provide a grate structure for use in such furnaces which will enable the fireman to obtain a quick response and secure an even control of the heat. A specific object is to provide a partition grate to divide the fire box into compartments side by side, the number of partition grates used depending on the number of compartments desired, so that when each alternate compartment is filled with coal, fire can be kindled in each remaining compartment and said fire allowed to eat its way into the fuel in the filled compartments.

The properties of subbituminous coal, such as is mined in Colorado and adjoining States, are such that the best results in firing are obtained when fire is allowed to eat its way into a pile of coal from the sides. Poking and stirring the coal is detrimental to the best results. For this reason I have provided the partition grate which will now be described.

Figure 1, denotes a cross sectional plan of a furnace containing my partition grate, taken on the line A—A in Fig. 2; Fig. 2, a vertical cross section of the furnace on the line B—B in Fig. 3; Fig. 3, a vertical cross section on the line C—C in Fig. 2; Fig. 4, a fragmentary cross section in elevation of a furnace showing a modified form of partition grate, and Fig. 5, a detail view of a support.

Although I show the preferred embodiment of my invention, I do not thereby limit myself to the precise form shown, but wish it understood that within the scope of what hereinafter is claimed various changes in the details of construction may be made, without departing from the spirit of the invention.

The reference character 1 denotes the shell of a furnace such as is commonly used in hot air heating plants; 2, the fire box wall; 3, the ash pit, and 4 the door. The horizontally disposed grate comprises bars 5, 6, 7, 9, 10 and 11, provided with triangular members 12 and mounted in the fire

box wall 2. A cog wheel 13 is mounted on bar 6 and meshed with cog wheel 14 mounted on bar 7. A similar cog wheel 15 is mounted on bar 9 and meshed with cog wheel 16 mounted on bar 10. The partition grate 55 comprises vertically disposed standards 18, 19 and 20 connected by horizontally disposed bars 8, 17 and 17^a. Bar 8 is provided with triangular grate members 21, and the middle bar 17^a, with bars 22 which terminate 60 so as to form an arch over the triangular members 21. A plurality of bars 17^b connect bars 17 and 17^a. The modification shown in Fig. 4, comprises a bar 24 mounted in lugs 25, and a plurality of bars 26 extending downward from bar 24 and terminating so as to form an arch.

In the drawings I have shown the fire box divided into two compartments, but with fire boxes of large grate areas I advise the 70 use of my partition grates to divide the fire box into a larger number of compartments so that each compartment will be of the proper size to facilitate firing by the method described.

The function of the arched portion in this grate structure is threefold as follows: The arrangement of the partition as well as its design is such that the unburned portion of the fuel remaining in the fire pot is separated 80 from the burning portion of the fuel by this partition, thereby permitting the fuel which is in a finely divided state, to burn only in a gradual manner, this manner of combustion then approaches that of solid 85 fuel, or fuel in lump form, this being the purpose of the grate. The arched opening in the partition mentioned above is to permit the gradual feeding of the fuel from the completely filled side of the grate to the side 90 that is burning, or burned out, thereby allowing a continuous combustion from one side of the partition to the other as the case might be. This arched opening, after having allowed the passage of a portion of the finely 95 divided fuel from the filled side of the partition to the side that is burning, forms a means of communication for the fire between the burned out side of the grate and the filled side. It allows the fire to progress 100

from one side of the grate to the other in order that the firing may be maintained continuously by means of firing alternate sides of the grate. It must be kept in mind that this grate structure was designed primarily for the combustion of finely divided or powdered fuels.

A compartment, as E, is filled with coal to the top of the partition grate. A fire is then kindled in compartment D. The fire in compartment D then eats its way under the arch and through other openings in the partition grate and consumes the coal in compartment E. When the fuel in compartment E has been reduced to a bed of live coals, compartment D is filled with fuel and the fire in compartment E eats its way into the pile of fuel in compartment D and reduces it to a bed of live coals, after which compartment D is refilled. This alternate filling of the compartments is kept up indefinitely. It will be noted that the coal is allowed to burn without poking or other disturbance except the shaking down of the ashes.

The ashes are shaken from compartment D by turning bar 7 which carries cog wheel 14 engaging cog wheel 13. This action turns bars 6 and 7, with their triangular members 12, and shakes down the ashes into ash pit 3. The ashes are shaken from compartment E by turning bar 9, which carries cog wheel 15 meshed with cog wheel 16.

In fire boxes of large area where several partition grates are used to divide the fire box into a number of compartments side by side, each alternate compartment is filled with coal and a fire is kindled in each remaining compartment so that the fires will eat into the fuel in the adjacent filled compartments.

I claim:

1. A grate of the class described comprising standards; two outside bars and a middle bar connecting said standards; triangular grate members on one of said outside bars; bars extending from said middle bar and terminating so as to form an arch over said triangular grate members; and bars spaced from each other connecting the remaining outside bar with said middle bar.

2. A grate of the class described comprising standards; main bars connecting said standards, one of said main bars being provided with a plurality of triangular grate members, and another one of said main bars being provided with a plurality of secondary bars extending therefrom and terminating so as to form an arch over said triangular grate members.

3. In combination with a fire box, a vertically disposed grate mounted in said fire box, said grate comprising vertically disposed standards; horizontally disposed main bars connecting said standards; triangular grate members on one of said main bars; and a

plurality of secondary bars depending from another of said main bars and terminating so as to form an arch over said triangular grate members.
